UNITED STATES PATENT OFFICE

170,129

COMBINED EXTINGUISHANT TANK AND HEAT COLLECTOR FOR PORTABLE FIRE EXTINGUISHERS

Peter Lim, Los Angeles, Calif.

Application January 30, 1952, Serial No. 18,301

Term of patent 14 years

(Cl. D16—2)

To all whom it may concern:

Be it known that I, Peter Lim, a citizen of the United States of America and a resident of Los Angeles, in the county of Los Angeles and State of California, have invented a new, original, and ornamental Design for a Combined Extinguishingant Tank and Heat Collector for Portable Fire Extinguishers, of which the following is a specification, reference being had to the accompanying drawing, forming part thereof.

Figure 1 is a side view of the combined extinguishingant tank and heat collector for portable fire extinguishers, showing my new design; and Figure 2 is a bottom plan view of the casing.

I claim:

The ornamental design for a combined extinguishingant tank and heat collector for portable fire extinguishers, as shown.

PETER LIM.
